(57) **CLAIM**

The ornamental design for an electric grinder, as shown and described.

DESCRIPTION

FIG. 1 is a front, right and top perspective view of a first embodiment of an electric grinder, showing my new design; FIG. 2 is a rear, left and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is a front, right and top perspective view of a second embodiment of the electric grinder; FIG. 10 is a rear, left and bottom perspective view thereof; FIG. 11 is a front, right and top perspective view of a third embodiment of the electric grinder; FIG. 12 is a rear, left and bottom perspective view thereof; FIG. 13 is a front elevation view thereof; FIG. 14 is a rear elevation view thereof; FIG. 15 is a left side elevation view thereof; FIG. 16 is a right side elevation view thereof; FIG. 17 is a top plan view thereof; FIG. 18 is a bottom plan view thereof; FIG. 19 is a front, right and top perspective view of a fourth embodiment of the electric grinder; and, FIG. 20 is a rear, left and bottom perspective view thereof. The broken lines in the figures depict portions of the electric grinder that form no part of the claimed design.

1 Claim, 20 Drawing Sheets
